COMBINATION COMB AND INSTRUMENT
CASE

Walter A. Wyman, Los Angeles, Calif.

Application May 17, 1937, Serial No. 143,029

5 Claims. (Cl. 132—79)

This invention relates to a combination pocket comb and an instrument case. The case or housing provided within the comb is more particularly intended to contain manicuring implements to be used in conjunction with the comb as an aid to maintaining the neatness and tidiness of the person using the device. However, if desirable, other small articles or implements may be housed within the comb.

It is a great convenience, particularly to traveling salesmen, clerks and other persons who, while away from home are especially desirous of maintaining a neat personal appearance, to have at hand a combination toilet article of the kind to which this invention pertains.

Among the objects of the invention are to furnish a combination toilet article of the above stated character which is an improvement over other toilet sets in respect to lowered cost of manufacture, simplicity of construction, convenience of using, and in other particulars, as will herein-after appear.

Referring to the accompanying drawing, which illustrates what is at present deemed to be a preferred embodiment of the invention,

Fig. 1 is a longitudinal mid section of the device on line 1—1 of Fig. 2.

Fig. 2 is a cross section thereof on line 2—2 of Fig. 1.

Referring in detail to the drawing, the comb body 10, desirably made of hard rubber, is of an elongated, flattened character and is furnished along one edge with the row of comb teeth 11, shown integral with said body.

Within the comb body 10 is encased an open-ended, flattened, tubular member 12, which, as shown, may have in its central portion an isthmus or contracted part 13. In the drawing a finger nail file 14 and a pair of tweezers 15 are shown, each of these instruments being almost entirely housed within the casing provided for them within the comb.

A valuable feature of the metal lining 12 having the contracted portion or isthmus 13 is that when a sharply pointed instrument of considerable length is inserted into an end portion of said lining the point of such instrument may extend beyond said isthmus without being blunted by contact with any part of the metal lining. The inserted instruments shown in Fig. 1 also are held in a centered position within the lining 12 by means of the inwardly bowed members of the pair of spring blades 16 located within each outer end portion of the housing formed by said

lining 12, thus keeping their edges as well as their points away from the metal lining.

When the comb body is made of rubber or "bakelite" and the metallic tubular member 12 is vulcanized or otherwise secured therewithin, a light, strongly reinforced structure results.

At each end of the tube 12 a concavity 12a is shown in each side to aid the operator in gripping between thumb and finger the manually withdrawable instrument desired.

A pair of spring blades 16 is secured to both outer edges of the tube 12, and extend into said tube with the inner ends of the pairs of spring blades bearing yieldingly together to frictionally hold instruments pressed therebetween in said tube.

I claim:

1. A device of the kind described having an elongated body portion consisting of an outer part of a relatively dense material and a tubular member of a flattened character and of denser, more resistant metallic sheet material embedded within said body and extending from end to end thereof, said tubular member being open at each end, there being a passage therethrough from end to end thereof, and diametrically opposed inwardly directed metallic spring members secured to said metallic sheet material adjacent to each end of said passage and positioned to yieldingly grip between them elongated implements inserted into the end portions of said passage.

2. A device of the kind described having an elongated body of relatively hard, firm material less resistant than metal, and a flattened tubular member of sheet metal embedded within said body and extending longitudinally thereof, said tubular member having an isthmus in its mid-length adapted to admit and to protect the point of an elongated pointed instrument housed within said tubular member.

3. A device of the kind described having an elongated body portion consisting of an outer part of a relatively dense material and a tubular member of a flattened character and of denser, more resistant metallic sheet material embedded within said body and extending from end to end thereof, said tubular member being open at each end, there being a passage therethrough from end to end thereof, and opposed inwardly directed spring members secured to said sheet material adjacent to each end of said passage and positioned to yieldingly grip between them elongated implements inserted into the end portions of said passage, said spring members consisting of pairs of resilient, convex blades having their convex-

ties directed toward each other, the members of each pair extending longitudinally of said passage.

4. A device of the kind described including a tubular member having an open end, and opposed inwardly directed spring members mounted adjacent to said open end, said spring members consisting of a pair of resilient, convex blades having their convexities directed toward each other, said blades extending longitudinally of said tubular member, and being positioned to grip inserted elongated implements between them.

5. A device of the kind described having an elongated body of relatively hard, firm material less resistant than metal, and a flattened tubular member of sheet metal embedded within said body and extending longitudinally thereof, said tubular member having an isthmus adapted to admit and to protect the point of an elongated pointed instrument housed within said tubular member. 5
